US0D1097398S

(12) **United States Design Patent** (10) Patent No.: **US D1,097,398 S**
(45) Date of Patent: ** Oct. 7, 2025

(54) **FLOOR CLEANING ROBOT**

(71) Applicant: **Alfred Kaercher SE & Co. KG**,
Winnenden (DE)

(72) Inventors: **Denis Dammkoehler**, Backnang (DE);
Yunjin Zhao, Winnenden (DE)

(73) Assignee: **Alfred Kaercher SE & Co. KG**,
Winnenden (DE)

(**) Term: **15 Years**

(21) Appl. No.: **29/876,539**

(22) Filed: **May 24, 2023**

(30) **Foreign Application Priority Data**

Dec. 16, 2022 (WO) WIPO126483

(51) **LOC (15) Cl.** **15-05**

(52) **U.S. Cl.**

USPC **D32/21**

(58) **Field of Classification Search**

USPC D32/21, 23, 19; D15/199; D21/526

CPC A47L 2201/00; A47L 5/30; A47L 11/4038

(57) **CLAIM**

The ornamental design for a floor cleaning robot as shown and described.

DESCRIPTION

FIG. 1 is a front, top and left side perspective view of a floor cleaning robot showing the new design;

FIG. 2 is a front, top and right side perspective view thereof;

FIG. 3 is a front elevational view thereof;

FIG. 4 is a left side elevational view thereof;

FIG. 5 is a rear elevational view thereof;

FIG. 6 is a right side elevational view thereof;

FIG. 7 is a top plan view thereof; and,

FIG. 8 is a bottom plan view thereof.

The broken lines in the drawings depict portions of the floor cleaning robot, and form no part of the claimed design.

1 Claim, 8 Drawing Sheets
